(57) CLAIM

The ornamental design for a merchandising display rack, as shown and described.

DESCRIPTION

FIG. 1 is a fragmented top, front, left side perspective view of a merchandise display rack showing our new design; FIG. 2 is a right side elevational view thereof, the left side being a mirror image of FIG. 2;

FIG. 3 is a fragmented top plan view thereof;

FIG. 4 is a fragmented front elevational view thereof;

FIG. 5 is a fragmented bottom plan view thereof; and,

FIG. 6 is a fragmented rear elevational view thereof.

The elements are shown as fragmented in the views to indicate a repeating pattern of indeterminate length.
